UNITED STATES PATENT OFFICE.

CLARKSON A. DISBROW, OF NEW ROCHELLE, NEW YORK, ASSIGNOR TO THE RAIL JOINT COMPANY, OF NEW YORK, N. Y., A CORPORATION OF NEW YORK.

LIGHTENED CONSTRUCTION FOR RAIL JOINTS.

Application filed November 15, 1928. Serial No. 319,649.

This invention relates to that type of rail joints wherein provision is made for an economical distribution of metal to render the bar comparatively light and yet possessing 5 adequate strength and stiffness for carrying the loading strains and stresses from the head to the foot portion of the bar.

Several types of construction have heretofore been designed and used having the same 10 general objects in view, but the present invention aims to provide a novel formation which can be embodied preferably in a rolled joint or splice bar and which will effect a very economical use of metal, particularly 15 throughout the region of the longitudinal neutral axis of the bar where the metal can best be spared. At the same time the invention provides for a novel reinforcement of the bar that will compensate for the lightening 20 of the web, and to so arrange the reinforcement as to enable the bar to easily carry the loads and stresses. Further, the invention contemplates a novel structural formation 25 throughout the web portion of the bar that will not only materially lighten the bar and reduce its weight, resulting in a reduced cost, but will also contribute materially to its flexibility so that the bar will more readily adapt itself to the rail wave motion without 30 danger of breakage.

With the above and other objects in view which will more readily appear as the nature of the invention is better understood, the same consists in the novel construction, combination and arrangement of parts herein-after more fully described, illustrated and claimed.

A preferred and practical embodiment of the invention is shown in the accompanying 40 drawings, in which:—

Figure 1 is a sectional perspective view showing the inside face of a bar embodying the present improvements.

Fig. 2 is a bottom plan view of the base 45 flange of the bar.

Fig. 3 is a sectional perspective view similar to Fig. 1 showing a modified arrangement.

Fig. 4 is a bottom plan view of the base 50 flange shown in Fig. 3, illustrating the modified arrangement of reinforcing elements.

Similar reference characters designate corresponding parts throughout the several figures of the drawings.

The present invention proposes to redis-

tribute and relocate the metal in a rail joint bar having a lightened web in such a way that the major reducement occurs adjacent the medial portion of the bar, that is, in the zone of the horizontal neutral axis of the bar. 60 While the invention thus described may be embodied in joint bars of various cross-sectional shape, nevertheless, for the purposes of illustration, the drawings show a conventional shape embodying an upright web 1, 65 the head 2, preferably of the reinforced type with the outer reinforcing rib 3, and the foot flange 4 which overlies the base flange of the rail.

Accordingly, the invention is more specifically concerned with the distribution of metal throughout the web portion of the bar and its reinforcement between the top and bottom chords of the bar toward the horizontal neutral axis thereof. 70

To that end the bar is made preferably by subjecting it to the various passes of a rolling mill so that in the final shape as it issues from the final pass of the mill the web of the bar 1 is of a subnormal thickness. That 80 is, of a materially less thickness than the normal thickness of standard angle bars or standard joint bars, and a major reducement in the thickness of the web occurs throughout the region of the horizontal neutral axis of 85 the bar indicated generally by the line N—A, being the region of the bar where metal can best be spared without being subjected to either compression or tension strains. This major reducement is rendered possible by the 90 special form of the reinforcing elements 5 which are formed integrally with the bar during the rolling operation.

As shown in Fig. 1 of the drawings these reinforcing elements are illustrated as being 95 of graduated thickness and in the form selected for illustration are preferably of a triangular or tapering shape extending respectively downwardly from the head of the bar and upwardly from the inside of the foot 100 of the bar to the region of the neutral axis of the web. These triangular or tapering reinforcements 5 are heaviest adjacent the top and bottom chords of the bar and gradually diminish in both width and thickness toward the medial line or neutral axis of the bar as 105 at 6 and in the form shown in Fig. 1 are joined or connected in a single integral formation.

The feature of lightening the bar may be further carried into effect in the foot flange 110

4. That is to say, the underside of the offset foot flange of the bar may be provided with a series of depressions producing a subnormal thickness of foot flange and the reinforcements 5^a which may be of substantially triangular formation and of gradually diminishing thickness from the bottom and outer chords of the bar toward the medial portion thereof to produce the formation 10 shown in Fig. 2. This construction materially reduces the metal in the foot flange of the bar without in any way sacrificing its strength or rigidity and at the same time provides adequate bearing contact between the 15 foot flange of the bar and the base flange of the rail.

By way of illustrating the range of modification of the invention, reference may be made to Figs 3 and 4 of the drawings, where- 20 in the reinforcements or ribs extending from the top and bottom chords of the bar toward the horizontal neutral axis are arranged in staggered relation and unconnected. These 25 reinforcements are designated as 7 and 8 respectively at the top and bottom of the web and are also of progressively tapered formation and diminishing thickness from the chord portions of the bar toward the medial line of the web. With this formation the fea- 30 ture of providing the major reducement in the zone of the horizontal neutral axis of the bar is preserved.

The same features of construction may be carried out in the foot flange 4^a of the bar 35 as illustrated in Fig. 4. In this figure the substantially triangular reinforcing fillets 7^a and 8^a are arranged in alternate or staggered relation and extend from the bottom chord of the bar and the outer chord of the bar inwardly toward the medial section of the foot flange, thereby preserving the full strength 40 and stiffness thereof and without sacrificing the clamping effect of the foot flange of the bar with reference to the base flanges of the 45 rail.

Without further description it is thought that the features and advantages of the invention will be readily apparent to those skilled in the art, and it will of course be 50 understood that changes in the form, proportion and minor details of construction may be resorted to, without departing from the spirit of the invention and scope of the appended claims.

55 I claim:

1. A rail joint bar including a web having displacements of metal producing graduated reinforcements extending from the top and bottom chords of the bar toward the medial portion of the web thereof.

60 2. A rail joint bar including a web having displacements of metal producing graduated triangular reinforcements extending toward the medial portion of the bar from the top 65 and bottom chords thereof.

3. A rail joint bar including a web having displacements of metal producing graduated triangular reinforcements having their apices extending toward the medial portion of the bar from the top and bottom chords thereof, 70 said reinforcements being of gradually diminishing thickness toward the neutral axis of the bar.

4. A rail joint bar including a web having displacements of metal producing a plurality 75 of reinforcing elements formed between the top and bottom chords of the bar and the web, said reinforcing elements being of minimum thickness adjacent the horizontal neutral axis of the web.

5. A rolled rail joint bar including a web having displacements of metal producing a plurality of reinforcing ribs extending from the top and bottom chords of the bar toward the horizontal neutral axis thereof, and said 85 ribs being of tapering formation and gradually diminishing thickness toward the horizontal neutral axis of the bar.

6. A rolled rail joint bar including a web having displacements of metal in one face thereof and arranged to provide stiffening ribs progressively diminishing in thickness from the top and bottom chords of the bar toward the horizontal neutral axis thereof.

7. A rolled rail joint bar including a web having displacements of metal arranged to produce reinforcing elements adjacent the top and bottom chords of the bar whereby the major reducement in the thickness of the web occurs in the region of the horizontal neutral 100 axis of the bar.

8. A rolled rail joint bar including a web having displacements of metal producing triangular reinforcements extending toward each other from opposite chords of the bar 105 and connected in a single integral formation.

9. A rolled rail joint bar including a web having displacements of metal producing triangular reinforcements of gradually diminishing thickness extending toward each other from opposite chords of the bar and connected in a single integral formation.

10. In a rolled rail joint bar, the combination of a web and a foot flange both having displacements of metal producing reinforcements extending from the chord portions of the bar respectively toward the medial portions of the web and the foot flange.

11. In a rolled rail joint bar, the combination of a web and a foot flange having displacements of metal at their inner faces and providing reinforcements extending from the chords of the bar respectively toward the medial portions of the web and foot flange, said reinforcements being of gradually diminishing thickness toward the medial portions of the bar.

In testimony whereof I hereunto affix my signature.

CLARKSON A. DISBROW.
